UNITED STATES PATENT OFFICE.

NOAH PAYNE, OF CHICAGO, ILLINOIS, ASSIGNOR TO PUGH STORES COMPANY, OF CHICAGO, ILLINOIS, A CORPORATION OF MAINE.

SHOE.

1,249,817.

Specification of Letters Patent. Patented Dec. 11, 1917.

Application filed January 27, 1917. Serial No. 144,809.

To all whom it may concern:

Be it known that I, NOAH PAYNE, a citizen of the United States, and a resident of Chicago, county of Cook, and State of Illinois, have invented certain new and useful Improvements in Shoes, of which the following is declared to be a full, clear, and exact description.

This invention relates to shoes, and its primary objects are to provide a shoe of neat and pleasing appearance, one that will hold its shape and is water proof. Another object is to provide a shoe, the vamp and top of which are constructed of woven fabric, such as silk, wool, linen, cotton or other cloth, having closely spaced rows of stitches throughout which not only give the shoe a distinctive and attractive appearance, but also prevent stretching and distortion of the shoe occasioned by the usual wear. A cloth shoe made in accordance with the present invention is not intended as a substitute for canvas shoes, but rather as a substitute for leather or other dress shoes. With the above mentioned objects and other advantages in view this invention consists in the several novel features hereinafter fully set forth and claimed.

The invention is clearly illustrated in the accompanying drawings, in which:

Figure 1, is a perspective view of a shoe embodying a simple form of the present invention; Fig. 2, is a detail enlarged section taken on line 2—2 of Fig. 1; Fig. 3, is a side view of one of the quarters, which forms the top of the shoe; Fig. 4, is a plan of the vamp; Fig. 5, is a detail enlarged section taken on line 5—5 of Fig. 1, and Fig. 6, is a detail enlarged section taken through a row of stitches.

Referring to said drawings, which illustrate one embodiment of the present invention, the reference numeral 10, designates the top, 11, the vamp and 12 the sole of a shoe embodying my invention; said parts may have any of the well known shapes employed in shoes.

A lining 13 (see Fig. 2) is provided as usual, and the top 10 and vamp 11, are sewed together, the sole attached to the vamp in the usual and customary manner, and the tongue and fastening devices are provided as usual, to make up a complete shoe.

The vamp is stitched with closely spaced rows of stitches 14, which run parallel with

the edge 15, that is, the U-shaped edge (see Fig. 4) which is secured to the top. It will be observed from an inspection of Fig. 4, that the stitches parallel the bend 16, of the edge 15, and that the radii of the curves of the rows of stitches around said bend 16, increase in diameter toward the outer edge of the vamp, that is, the edge which is secured to the sole. Said rows of stitches are made on a sewing machine, and are put as closely together as the operator can make them. The result is that the cloth is reinforced throughout by the stitches, although it remains pliable, and because of the direction taken by the rows of stitches, the vamp cannot stretch to any appreciable extent in either direction. It is to be observed that in the finished shoe (see Fig. 1) the rows of stitches run in lines paralleling the edge 15, and that across the toe portion of the shoe they curve upward from the sole and run across the toe portion, then down to the sole on substantially the same curved lines.

The top members 10, if desired may have closely spaced rows of stitches 17, formed therein, preferably paralleling the front and top edges 18, 19. (See Fig. 3.) In constructing the top of a shoe embodying the present invention, two or more pieces 20, 21, of woven fabric (see Fig. 2) such as silk, wool, cotton, linen, etc., are cut to the proper shape, placed coincident with each other and the edges turned in as seen in Fig. 2. The pieces 20, 21, are then stitched together, the first rows of stitches being placed at the edge 18, 19, (see Fig. 3) and running substantially parallel. It is to be observed that the entire surface of the top may be covered with the stitches although for simplicity in illustrating the invention, the stitches have been omitted from a portion of the top in Fig. 3.

In constructing the vamp, two or more layers of woven fabric having the shape of the vamp, are employed, and preferably three layers 22, 23, 24, are employed (see Fig. 6) the intermediate layer 23, being water-proofed on one side, 25, or both sides, or made impervious to water in any suitable manner, as for instance, the intermediate layer may be impregnated with a water proof material.

The edges 15, of the outer layers are turned in (see Fig. 5) and the rows of stitches are made beginning at the turned in

edges. It is to be understood that the entire surface of the cloth vamp portion is covered with rows of stitches, and for the purpose of simplifying the illustration 5 stitches are shown only on part of the surface in Fig. 4.

When the top and vamp have been prepared as described they may be sewed together and sewed to the lining and sole, and 10 other necessary parts added to complete the shoe in accordance with the common practice.

As previously stated, the rows of stitches are made close to each other. That is to say, 15 they should be made practically contiguous, but not touching each other. The rows of stitches should be placed so close to each other that in place of the quilted effect obtained in stitched cloth or felt shoes, a new 20 and novel material is produced one that is firm and yet flexible, and practically non-stretchable. Furthermore, by placing the rows of stitches contiguous with each other, the several plies or layers of materials are 25 so united by the stitches as to have the wearing qualities of leather. To obtain this result in the most effective manner, the spaces between the rows of stitches should not exceed the length of the stitches themselves. 30 Stitches not more than one sixteenth of an inch in length have been found to produce the desired result.

From the above, it will be observed that the stitches add strength and durability to 35 a shoe made of cloth or other woven fabric; that when stitched in the manner described the shoe holds its shape, and by reason of the water-proofing material the interior of the shoe is kept dry. Furthermore, any desirable color of cloth and thread may be used, 40 either in heavy or light weight.

I desire it to be understood that the term "shoe" as herein used includes high shoes, 45 low shoes, slippers, boots and the like.

More or less variation of the exact details of construction shown and described is possible without departing from the spirit of this invention. I desire, therefore, not to

limit myself to the exact form of construction shown and described, but intend in the 50 following claims to point out all of the invention disclosed herein.

I claim as new and desire to secure by Letters Patent:

1. A shoe having a cloth vamp, there being 55 contiguous rows of stitches throughout the same.

2. A shoe having a cloth vamp, there being 60 contiguous rows of stitches in said vamp paralleling the upper edge thereof and extending throughout the vamp.

3. A shoe having a cloth vamp, there being 65 contiguous parallel rows of stitches throughout the vamp, and said stitches running lengthwise of the sides of the vamp 70 and merging into curved lines crossing the same at the toe portion.

4. A shoe having a cloth vamp, comprising 75 a plurality of layers of cloth stitched together throughout, the rows of stitches being parallel and contiguous.

5. A shoe having a cloth vamp, comprising 80 outer cloth layers, and an inner waterproofed layer, all stitched together throughout, the rows of stitches being parallel and contiguous.

6. A shoe having a cloth vamp comprising 85 outer cloth layers and an intermediate cloth layer waterproofed on one side, said layers being stitched together throughout along contiguous rows extending parallel with each other.

7. A shoe having a top and a vamp sewed 90 together, and having closely spaced rows of stitches throughout, the stitches of the top paralleling its front and top edges, and the stitches of the vamp paralleling the upper edge thereof.

8. A shoe having a vamp and a top, the 95 vamp having closely spaced parallel rows of stitches paralleling its upper edge, and the top having closely spaced parallel rows of closely spaced stitches paralleling its front and top edges.

NOAH PAYNE.
